UNITED STATES PATENT OFFICE.

JAMES E. WARLICK, OF LAGRANGE, GEORGIA.

COMBINED FAUCET AND MEASURER.

No. 802,895.

Specification of Letters Patent.

Patented Oct. 24, 1905.

Application filed June 16, 1905. Serial No. 265,580.

To all whom it may concern:

Be it known that I, JAMES E. WARLICK, a citizen of the United States, residing at La-
5 grange, in the county of Troup and State of Georgia, have invented new and useful Im-
provements in a Combined Faucet and Mea-
sure, of which the following is a specification.

My invention relates to improvements in
combined faucets and measures.

10 It has primarily for its object the drawing off and simultaneously measuring the fluid or liquid from a barrel or cask and the delivering of the measured fluid or liquid into the receptacle for receiving it.

15 The nature of the invention consists of cer-
tain structural features substantially as hereinafter fully disclosed and particularly noted.

In the hereto-annexed drawings, Figure 1
20 is a side view, and Fig. 2 is a sectional view,
of the preferred embodiment of my invention.
Fig. 3 is a view in side elevation showing
the device in its discharging position.

In carrying out my invention I provide
25 a suitable tubular elbow 1, preferably com-
posed of practically two screwed - together
pipe-sections 1^a 1^b, with one end of the latter
pipe-section screwed into the liquid-contain-
30 ing barrel or cask and the other pipe-section
connecting with and terminating in a hollow
axial member 1^c, produced with a port 1^d in
its upper surface and somewhat tapering for
a purpose later apparent.

A preferably circular measuring receptacle
35 or drum 2, which may have a capacity of one
pint or one quart, has passing therethrough
a central hub or sleeve 2^a of corresponding
taper as and receiving the axial member 1^c,
and upon which latter said drum is adapted
40 to be turned, and which hub or sleeve has a
port 2^b for registration with the port 1^d of
said axial member. Said axial member has
its smaller tapered end projecting beyond said
receptacle or drum and provided with a shoul-
45 der 1^e and a screw-threaded surface beyond
the latter, and upon said shoulder is inserted
a washer 1^f, and upon said screw-threaded
surface is screwed a nut 1^g up against said
washer for suitably holding the drum or
50 receptacle rotatably in position upon said axial
member. By suitably screwing up the ta-
pered axial member, as will be readily un-
derstood, the parts may be caused to fit air-
tight. Said axial member has also a lateral
55 stud or projection 1^h, engaging an extension
2^c of the hub or sleeve 2^a, serving as a stop
for predetermining the extent of the turning

of the measuring receptacle or drum in ef-
fecting registration between the ports 1^d and
2^b, above noted.

In the perimeter of the receptacle or drum 60
2 is a spout 2^d, arranged diametrically in aline-
ment with the port 2^b of the latter and hav-
ing a lateral nozzle 2^e, to which is applied one
end of a section of hose 3, and as a continua-
65 tion of the last noted is employed a hose-sec-
tion 3^a, interposed between which and forming
a continuation thereof is a glass or trans-
parent tube 3^b for visually ascertaining when
the drum or receptacle has reached the filled
70 state, as will be readily understood. Like-
wise arranged in diametric alinement with the
port 2^b and also in the perimeter of the drum
or receptacle 2 is an air-valve 4, with its disk
or washer member held automatically upon
75 its seat within said drum by a spring 4^a, en-
compassing its headed stem, and by pressing
upon the latter with the finger or thumb said
valve may be opened, as in emptying the drum
of its contained liquid.

In operation it will be noted that the drum
being adjusted to bring the ports 1^d 2^b into
registration and the finger placed over the
end of the spout 2^d the liquid from the barrel
or cask entering the elbow or pipe connection
1 will flow through said ports into said drum
85 or receptacle and fill the same, that fact being
indicated by the liquid rising into the nozzle
2^e and entering the hose-sections and the glass
tube 3^b. The drum is now turned to the left,
immediately of course cutting off the flow of
90 the liquid or fluid and the drum permitted to
be emptied of its contents through the spout
2^d, said drum being turned until the spout has
been presented directly downward and said
contents or liquid entering a vessel or recep-
95 tacle suitably placed for that purpose.

I claim—

1. A device of the character described, com-
prising a rotatable drum having a discharge-
tube in its perimeter and a central ported hub
100 or sleeve through its center, and a supply tube
or pipe having a ported member forming an
axis for said drum and means for limiting or
predetermining the movement of said drum.

2. A device of the character described, com-
prising a rotatable drum having a discharge-
tube in its perimeter, provided with a nozzle
105 suitably equipped for indicating the filling of
said drum, and a supply tube or pipe having a
ported member forming an axis for said drum,
and means for predetermining the movement
110 of said drum.

3. A device of the character described, comprising a rotatable drum having a supply tube or pipe passing centrally therethrough and having a ported member serving as an axis for said drum, said drum also having a discharge-spout and an air-valve said spout being arranged in alinement with the port of the hub or sleeve of said drum, and having a lateral nozzle equipped to indicate the filling of

said drum, and means for predetermining the movement of said drum.

In testimony whereof I affix my signature in presence of two subscribing witnesses.

JAMES E. WARLICK.
